2 Claims. (Cl. 328—8)

In converters of the ionic valve (current rectifier) type having several parallel-connected anodes which must ignite simultaneously there is a risk of unequal distribution of the current, i.e. one anode may receive current greater than any of the others. If this unequal distribution is noticeably large and also continues for a long time it may lead to overloading and damage to the anode. It is of course possible to connect over-current relays in each anode conductor and on each relay arrange an optical or acoustic signal or a combination of both, which is emitted when a fault occurs, but this presupposes that personnel are available to observe the signal. Converter ionic valves for high voltage direct current are extremely safe in operation and the ionic valve rooms therefore seldom need inspecting by the station personnel. It is thus desirable for a fault of the nature mentioned in the introduction to be remotely indicated where the personnel are. However, the anodes are situated at a potential of the order of magnitude 100 kv. and it is therefore inconceivable to use normal transmission of the measured value or signals by wires.

The present invention solves the problem by transmitting a signal from the high anode potential to earth. According to the invention each anode is provided with a thermal releasing device influenced by the anode current and with a gas valve controlled by the thermal releasing device, the valve being connected in a tube system of insulating material so that it can influence the gas pressure in a gas container situated at the earth potential and provided with a pressure-sensitive measuring means.

In the accompanying drawings, FIGURE 1 shows schematically one embodiment of the invention, while FIGURE 2 shows the gas valve used.

FIGURE 1 shows the invention for use with an ionic valve having four anodes. The valve housing which contains a cathode or cathodes, is designated 1. Each anode is enclosed in an insulator tube positioned on the valve housing and said anode insulator is surrounded by an outer tube 2 of insulating material. The anode insulators support an air drum 3 which, together with the tubes 2, forms an air cooling system for the anode insulators. In each anode conduit a thermal releasing device is connected in parallel. The releasing device consists of a heating body which is heated by a current proportional to the anode current. The alternation in length of the heating body, through a snap mechanism, controls the releasing arm 6 shown in FIGURE 2 at one end 7 of the heating body. The releasing arm 6 is pivoted at 8 and its other end 9 is arranged to engage a knob 10 acting as a block on a valve rod 12 connected to the gas valve 11. In FIGURE 1 the arrangement for the action of the releasing device 5 on the gas valve 11 is schematically indicated by the connection 13.

Into the left-hand gas valve 11a shown in FIGURE 1 a tube 14 opens, made of an electrically insulating material, preferably plastic. At the other end the tube is connected to a gas container 15 in which gas, suitably air, is by means of a pumping means, not shown, maintained at a certain pressure. Thus, the tube 14 acts as an inlet for the gas from the container 15 to the left-hand valve. Inside the valve housing the tube 14 ends

2

in a valve seat 16. From the valve housing an outlet tube 17 leads to the next valve 11b so that the tube 17 acts as an inlet to the last mentioned gas valve from the container 15. In the same way the valve 11b is connected to the valve 11c by means of a tube 18 and the valve 11c is connected with the valve 11d by means of a tube 19. The outlet tube 20 from the valve 11d is led to a cylinder 21 at the earth potential, said cylinder containing a spring-influenced piston 22 which is arranged to operate a contact 23.

On the valve rod 12 in the valve housing to the gas valve 11 is attached a valve plate 24 provided on both sides with seals. A spring 25, which is arranged between the valve housing and a projection 26 on the valve rod, tends to press the valve rod downwards so that the valve plate will abut the valve seat 16 and thus close the inlet tube 14. In its upper position the valve plate abuts an upper valve seat 27 which is arranged on an intermediate wall 28 in the valve housing. Between the valve rod 12 and the upper valve seat there is a cylindrical channel 29. The valve rod is kept in its upper position by the lever 6 which abuts the under side of the knob 10. If the valve rod and valve plate have taken up their lower positions because the releasing device 5 has swung the releasing arm 6 away from the knob 10, the valve rod can be returned to its upper position by a lever 30 and a pullthread 31. In the part of the valve housing situated above the dividing wall 28 are one or several holes 32 which join the upper part of the valve housing with the outer air. The releasing device 5 is provided with a flag to indicate that release has taken place.

The arrangement operates in the following way. If the current in any of the anode conduits 4, due to unequal loading, exceeds the value set on the corresponding thermal releasing device 5, the releasing device influences the lever 6 so that the valve rod 12 is released and the valve plate 24 is pressed against the valve seat 16 so that the tube 14 is shut off from the inside of the valve housing. At the same time as the valve plate 24 leaves its upper valve seat the tube 17 will be placed in communication with the open air via the lower part of the valve housing, the cylindrical channel 29, the upper part of the valve housing and the holes 32. The pressure in the entire succeeding part of the tube system and also in the following gas valves will then drop to atmospheric pressure. The spring in the cylinder 21 presses the piston 22 to the left so that the contact 23 closes and a signal is given.

In the embodiment of the invention shown all the gas valves belonging to the same ionic valve are series-connected. It is of course possible to parallel-connect them to a common feeding tube from the pressure container 15 so that each gas valve with its releasing device operates and gives signals independently of the others. Other modifications of the invention are also conceivable.

I claim:

1. Means for indicating overload current in multiple anode ionic valves, comprising, for each anode, a thermal releasing device responsive to variations in the anode current and a gas valve controlled by said thermal releasing device, each said gas valve comprising a valve housing with inlet and outlet tubes and spring actuated valve means in said valve housing operatively connected to said thermal releasing device for normally connecting the inlet and outlet tubes to each other, said valve means including means responsive to a release impulse from said thermal releasing device for cutting off such connection and establishing a connection between the outlet tube of such gas valve and the atmosphere, a gas container, means connecting said gas container to the inlet tube of the valve housing of a first of said gas valves, means connecting the outlet tube of each gas valve other than the

last gas valve to the inlet tube of the next gas valve, a pressure sensitive measuring device, and means connecting the outlet tube of the last of said gas valves to said pressure sensitive measuring device.

2. Means according to claim 1, the valve housing of each gas valve being provided with at least one gas discharge hole which connects said outlet tube to the atmosphere when said valve means cuts off the connection between said outlet and inlet tubes, thereby connecting said pressure sensitive measuring device to the atmosphere, said gas discharge hole constituting a part

of said means for establishing the connection between the outlet tube and the atmosphere.
